DESIGN FOR A SPOON OR OTHER ARTICLE OF FLATWARE

James Russell Price, Providence, R. I., assignor
to Gorham Manufacturing Company, Providence, R. I., a corporation of Rhode Island

Application March 4, 1938, Serial No. 75,567

Term of patent 14 years

To all whom it may concern:

Be it known that I, James Russell Price, a citizen of the United States of America, of 2335 Cranston Street, Providence, Rhode Island, have invented a new, original, and ornamental Design for a Spoon or Other Article of Flatware, of which the following is a specification, reference being had to the accompanying drawing, forming part thereof.

Figure 1 is the obverse side of a spoon showing my new design, and Figure 2 is a side view of the same. Figure 3 shows the reverse side of the spoon, while Figure 4 is a cross section of said spoon taken on line 4—4 in Figure 1.

I claim:

The ornamental design for a spoon or other article of flatware, substantially as shown.

JAMES RUSSELL PRICE.
